UNITED STATES PATENT OFFICE.

WILLIAM MURRAY, OF WOODHAVEN, NEW YORK, ASSIGNOR TO GENERAL CHEMICAL COMPANY, OF NEW YORK, N. Y., A CORPORATION OF NEW YORK.

CARBOY BOTTLE.

Application filed November 17, 1923. Serial No. 675,275.

My invention relates to carboy bottles and more particularly to that class thereof in which acids and other highly corrosive liquids are stored and shipped. Such carboy bottles are generally closed by means of suitable stoppers and gaskets which lie between an overhanging portion of the stopper and the peripheral edge of the mouth of said carboy bottle. These peripheral edges, in use, become chipped and thus very often reduce the sealing efficiency of the gaskets. Because of the capacity of these carboy bottles the contents thereof represent considerable volumes of liquid which, when the carboys are in transit and subject to continued vibration or due to the fact that said carboys are awkward to handle, and often are set down with a jar or shock, is set in motion and develops considerable energy. The latter often results in causing a violent rebound of the liquid contents, which as a result are thrown against the gasket and oftentimes squirt out through the spaces between the latter and the chipped edges of the mouth of the carboy bottle in what is commonly known as an acid or other splash. If the contents are acids or other corrosive liquids, these repeated splashes will finally destroy the gasket and in any case will bring about a leakiness of the carboy closure. As a result such carboy bottles with the existing type of closures, have come to be regarded as an inefficient and even dangerous means for conveying acids and other liquids. The object of the present invention is the provision of a carboy bottle of novel construction and having a novel closure whereby the harmful effects of the development of the aforesaid energy in the liquid contents are neutralized and all of the disadvantages recited hereinbefore together with the elements of danger and the possibility of acid or other splash are entirely eliminated. Other more specific objects of the invention will appear from the description hereinafter.

In the accompanying drawings, which illustrate an example of the invention without defining its limits, Fig. 1 is a fragmentary, vertical section of the carboy bottle and Fig. 2 is a horizontal section on the line 2—2 of Fig. 1.

As shown in the drawing, the carboy bottle comprises a body 5 which may be of any conventional form and size, and a continu-

ing neck 6 having the customary tapering head 7 and external shoulder 8 located at a distance from the mouth of the bottle; the peripheral edge 9 of the neck 6 is preferably rounded in the well known way as illustrated. The neck is formed with an outlet bore 10 which extends inwardly from the edge 9 and terminates at an annular shoulder 11 located interiorly of said neck at a considerable distance inwardly from its mouth or specifically from said edge 9. The surface of the shoulder 11 projects inwardly from the surface of the bore 10 in a direction transverse to the major axis of the carboy as shown in Fig. 1. From the shoulder 11 the interior surface of the neck may diverge or flare directly from the inner peripheral edge of said shoulder to form an inwardly diverging bore as indicated at 12 and merge into the inner surface of the body 5 along smooth lines free from any sharp bends or other obstructive surface conformation.

In practice an annular packing or gasket 13 preferably of asbestos wicking is located in engagement with the shoulder 11 and is preferably of such inner diameter as to bring its inner surface substantially in registry with the inner peripheral edge of said shoulder as shown in Fig. 1. The packing 13 is adapted to be engaged by a stopper 14 of suitable material which preferably is of such diameter as to fit within the bore 10 and is provided with a head 15 arranged to overlap the peripheral edge 9 of the neck 6 when the stopper is in position therein. The stopper 14 is fixed in place, in the neck, in any conventional manner as by means of wiring 16 which extends beneath the external shoulder 8; the arrangement is such that by the action of the wiring 16 the stopper 14 engages the packing or gasket 13 under pressure so as to efficiently seal the carboy bottle against leakage. In the preferred construction the stopper 14 is provided with means for simplifying the method of placing the gasket 13 in its proper place in order to seal the carboy bottle, for eliminating the danger of said packing shifting or falling into the container and for avoiding splash. The means in question also prevents the liquid from coming into contact with the seal and thereby avoids any possibility of acid splash even though the packing 13 is not in place. In the illus-

trated example the means referred to comprises a cylindrical extension 17 projecting axially from the inner end of the stopper and of such diameter as to fit within and receive the packing 13. The extension 17 is preferably of sufficient axial length to extend beyond the annular shoulder 11 and into the diverging bore 12 of the neck as shown in Fig. 1, when the stopper is in place.

With the arrangement shown and described the sealing of the carboy bottle is effected at a point within the neck and independently of the peripheral edge 9 or the head 15 of the stopper 14; that is to say, the co-operation of the stopper 14, the gasket or packing 13 and the interior shoulder 11 at a point within said neck is the medium whereby closure of the carboy is efficiently brought about. Any agitation, rebound or otherwise, of the liquid contents will at no time result in any of said contents passing the packing 13 which consequently retains its efficiency throughout its natural period of usefulness. The condition of the peripheral edge 9, whether perfect, chipped or broken, will have no effect upon the efficiency of the seal or closure and may be entirely disregarded. The so-called acid splash, with its resultant danger, which is so often present in existing carboy bottle is entirely eliminated and the carboy bottle, constructed and sealed according to the present invention, is consequently a safe and efficient medium for storing and conveying acids and other highly corrosive or otherwise dangerous liquids. The carboy bottle, embodying the improvements herein described may be tilted in the same way as any existing carboy bottle or placed in any position without having the acid or other contents ooze through the gasket or packing 13. The bore 12 which as before stated may diverge directly from the inner shoulder 11 and merge into the body 5 provides a continuous free passage for the contents and permits the same to be poured from the carboy without hindrance.

It is to be understood that the invention relates primarily to carboy bottles, which generally speaking are of large capacity and because of this, when subjected to vibration, shocks or other movements bring about the development of considerable energy in the large volumes of liquid represented by the contents of said carboy bottles. The energy referred to results in a condition which includes special problems not found in ordinary bottles, in which because of the relatively small volume represented by the contents, any energy which may flow from a movement therein is negligible and without effect upon the closure or seal of such ordinary bottles. With carboy bottles this developed energy, on the other hand, is sufficient to

cause existing closures to leak and to permit what is commonly referred to as "acid splash", a serious and dangerous condition which the present invention overcomes completely.

Various changes in the specific form shown and described may be made within the scope of the claims without departing from the spirit of the invention.

I claim:

1. A carboy bottle of relatively large liquid capacity arranged to contain a relatively large volume of liquid capable of developing considerable energy when set in motion, said carboy having a neck provided with a peripheral edge liable to become chipped, said neck having an outlet bore and an inwardly flaring bore communicating with the body of the carboy bottle, an annular shoulder located exteriorly upon said neck, an annular shoulder located interiorly of said neck at a considerable distance inwardly from said peripheral edge at the opposed terminations of said outlet bore and inwardly flaring bore, a stopper fitted into said neck, a packing located between said shoulder and an opposed surface of said stopper to seal said carboy bottle against "liquid splash" resultant from the energy developed in said liquid, regardless of the condition of the aforesaid peripheral edge and fastening means engaging said exterior shoulder and said stopper to force the latter against said packing under pressure.

2. A carboy bottle of relatively large liquid capacity arranged to contain a relatively large volume of liquid capable of developing considerable energy when set in motion, said carboy having a neck provided at its outlet end with a peripheral edge liable to become chipped, said neck having an outlet bore and an inwardly flaring bore communicating with the body of the carboy bottle, an annular shoulder located interiorly of said neck at the inner end of said outlet bore and projecting inwardly therefrom toward the axis of said neck into connection with the terminating end of said inwardly flaring bore, an annular packing engaging said shoulder entirely within the neck, a stopper having a portion fitting said outlet bore and engaging said packing, an annular shoulder located exteriorly upon said neck and fastening means engaging said exterior shoulder and said stopper to force the latter against said packing under pressure to seal said carboy against "liquid splash" resultant from the energy developed in said liquid regardless of the condition of the aforesaid peripheral edge.

3. A carboy bottle of relatively large liquid capacity arranged to contain a relatively large volume of liquid capable of developing considerable energy when set in

motion, said carboy having a neck provided with a peripheral edge liable to become chipped, said neck having an outlet bore and an inwardly flaring bore communicating with the body of the carboy bottle, an annular shoulder located exteriorly upon said neck, an annular shoulder located interiorly of said neck at a considerable distance inwardly from said peripheral edge 5 at the opposed terminations of said outlet bore and inwardly flaring bore, an annular packing engaging said interior shoulder entirely within said neck, a stopper adapted to abut against said packing, means cooper-

ating with said exterior shoulder and said stopper to force the latter against said packing under pressure to seal said carboy bottle against "liquid splash" resultant from the energy developed in said liquid regardless of the condition of the aforesaid peripheral 20 edge and a cylindrical extension on said stopper fitting within said packing and projecting into said inwardly flaring bore to protect the packing against contact with the contents of said carboy bottle. 25

In testimony whereof I have hereunto set my hand.

WILLIAM MURRAY.
